DRAFTING TABLE OR SIMILAR ARTICLE

Solomon Rosenthal, 134½ N. Swall Drive,
Beverly Hills, Calif.

Filed Sept. 24, 1962, Ser. No. 71,822

Term of patent 14 years

(Cl. D33—14)

FIG. 5.

FIGURE 1 is a side elevational view of a drafting table or similar article showing my design;

FIG. 2 is a top plan view thereof;

FIG. 3 is a view taken from the direction of the arrow 3 in FIG. 1;

FIG. 4 is a rear view taken from the direction of arrow 4 in FIG. 1; and

FIG. 5 is a perspective view taken from the side opposite that shown in FIGURE 1 and showing the drafting table or similar article on an enlarged scale.

I claim:

The ornamental design for drafting table or similar article, substantially as shown.
